ABSTRACT OF THE DISCLOSURE

A center plate for a railway car body having a cushioned underframe includes a top wall, a bottom wall having an annulus, side walls sloping outwardly from the top wall to the bottom wall and sloping longitudinally inwardly near their ends, lateral walls extending from the side walls for supporting a sliding center sill, vertical and angular support walls extending along the length of the lateral walls, and transverse ribs and longitudinal arcuate members supporting the underside of the structure.

This invention relates to railway car underframes and more particularly to a new and improved body center plate construction, particularly suitable for use with cushioned underframes having sliding center sills.

Because the distance outboard from bolster centers to strikers on many railroad cars is relatively short, the installation of energy absorbing arrangements in these areas has not been feasible. This has lead to the development of cushion underframes wherein a sliding sill extends longitudinally through the car from coupler to coupler with an energy absorbing device interposed therein. Supporting ribs between fixed sills must be removed, and space limitations necessitate a body center plate construction that will provide maximum support when the car is rocked or tilted and yet accommodate the sliding center sill and provide clearance for draft lugs.

Accordingly, an object of this invention is to provide a body center plate construction having maximum support characteristics within a limited area.

The above and other objects, which will become apparent to those skilled in the art, will appear hereafter in the specification and appended claims and in connection with the accompanying drawings wherein:

FIGURE 1 is a plan view of a body center plate embodying the invention described herein;

FIGURE 2 is a cross-sectional view through section lines 2—2 of FIGURE 1, and shows the relation of the center plate to associated parts (shown in outline) of a railway car;

FIGURE 3 is a cross-sectional view of the article shown in FIGURE 1, taken through section lines 3—3; and

FIGURE 4 is a side elevation view of the body center plate shown in FIGURE 1.

The improved center plate shown in the figures is a unitary composite structure having a main box portion, generally indicated by 18, with a substantially rectangular flat top wall 20 and an undulated bottom wall portion 22 defining a central annulus 24 for engagement with a mating truck bolster center plate (not shown). As shown in FIGURE 2, side walls 26 and 28 of box portion 18 slope downwardly and outwardly from top wall 20 to bottom wall 22 toward a line near the outer circumference 30 of annulus 24. As shown in FIGURE 1, side walls 26 and 28 also slope longitudinally inwardly from points on either side of the outer circumference 30 of annulus 24 toward their respective edges, thereby providing clearance for the draft lugs 54 secured within a sliding sill 53, one position of such a lug being indicated by dotted lines at 32 (FIG.

2

1). The ends of side walls 26 and 28 also extend beyond the length of rectangular top wall 20, and the upper edges 12 of said ends slope outwardly from the corresponding corners 13 of said top wall to the corresponding lower corners 14 of said side walls.

5 A central vertical passage 27 for a king pin (not shown) through and between top wall 20 and bottom wall portion 22 is defined by an annular vertical wall 29 extending between said top and bottom walls, the top section 15 of said annular wall being substantially cylindrical in shape, the central portion 16 thereof flaring outwardly, and the bottom portion thereof 17 flaring outwardly to a lesser degree than said central portion, toward the bottom wall portion 22.

10 Extending outwardly from side walls 26 and 28, along the lengths thereof, are integral lateral walls 34 and 36, the respective upper surfaces thereof 35 and 37 having flat pads 39 located at opposite ends of said upper surfaces, which pads support the feet 54 of an inverted U-shaped

20 sliding sill 53 (FIG. 2). Secured near the outer side extremities of lateral walls 34 and 36 are vertical wall supports 38 and 40, which extend along the length of their respective lateral walls. Also extending upwardly from the outer side extremities of lateral walls 34 and 36 are angularly disposed welding flanges 42 and 44, which also extend along the length of their respective lateral walls and have a plurality of spaced openings 45 formed therein for welding to respective body bolster cover plates 57 and 55 secured to fixed sills 51 and 58, respectively.

25 Bottom wall 22, lateral walls 34 and 36, welding flanges 42 and 44, and the portions of side walls 26 and 28 extending beyond the extremities of main box portion 18 are supported by integral hollow transverse ribs 46 and 48 secured underneath the composite structure, proximate

30 its ends. Transverse ribs 46 and 48 are rectangular in cross section and extend between the lower portions of welding flanges 42 and 44. Extending between respective transverse ribs 46 and 48, proximate the sides of the composite structure, are arcuate longitudinal support members 50 and 52, the ends thereof terminating beneath related pads 39 approximately centrally of said pads. A plurality of

35 spaced transverse supporting arms or ribs 54 extend from arcuate support members 50 and 52 from intermediate the ends thereof to their adjacent welding flange 42 or 44. The outer end portions of transverse ribs 46 and 48, transverse arms or ribs 54 and the inner portions of welding flanges 42 and 44 form pedestals 60 and 62 for support of fixed sills 51 and 58. Pedestals 60 and 62 provide an additional safety feature in that they will support the weight of the car in the event that the welding flanges 42 and 44 break or the welds to body bolster cover plates 57 and 55 fail.

40 It may now be seen that the structural arrangement of the center plate described herein allows the transfer of forces from annulus 24 and main box portion 18 toward the outer periphery of the structure; hence, forces are transferred to transverse ribs 46 and 48 and arcuate longitudinal support members 50 and 52, whereby the requisite support during rocking or tilting is attained within a limited space. Also, each pad 39 is reinforced below the center thereof by one end of an arcuate support member 50 or 52 at its merger with a related transverse rib 46 or 48.

45 It will also be understood that various changes in the details and arrangements of parts, which have been herein described and illustrated in order to explain the nature of the invention may be made by those skilled in the art.

Having thus described the invention, what is claimed is:

1. A railway car body center plate of unitary composite structure comprising a bottom wall having an annulus for

engagement with a mating truck bolster center plate, a top wall, and a pair of spaced side walls continuously interconnecting said top wall and said bottom wall along substantially their entire length, said side walls each sloping outwardly from said top wall to said bottom wall toward the outer circumference of said annulus.

2. The invention according to claim 1 wherein said center plate has a central vertical passage comprising a central annular inner wall between said top wall and said bottom wall, the lower section of said inner wall being flared outwardly.

3. The invention according to claim 1 wherein lateral walls extend from said side walls and include means at the extremities thereof for attachment to a car underframe.

4. The invention according to claim 3 wherein transverse support ribs are secured across said bottom wall and said lateral walls on the underside of said structure, proximate the ends thereof.

5. The invention according to claim 3 wherein an arcuate longitudinal support member is secured beneath each lateral wall and interconnects said transverse support ribs.

6. The invention according to claim 3 wherein said means for attachment to a car underframe comprise vertical support walls and angularly disposed welding flanges extending from the extremities of said lateral walls.

7. The invention according to claim 1 wherein said side walls slope longitudinally inwardly from points outside the outer circumference of said annulus.

8. In combination with a railway cushioned underframe wherein a center U-shaped sill member is detached and permitted to drive longitudinally in either direction while sliding on the body center plate, the improvement in center plate construction which comprises a unitary composite structure having a top wall of substantially rectangular shape, a bottom undulated wall defining a central annulus for engagement with a mating truck bolster center plate, side walls sloping outwardly from said top wall to said bottom wall toward a line outside the outer circumference of said annulus, said side walls sloping longitudinally inwardly from points outside the outer circumference of said annulus and extending beyond the ends of said top wall, lateral walls extending from said side walls and comprising support means for a sliding sill, vertical support walls at the outer sides of said lateral walls extending along the length of said lateral walls, welding flanges disposed outwardly and upwardly along the length of said lateral walls, a transverse rib supporting the underside of the composite structure at each end thereof, and an arcuate longitudinal member extending between said transverse ribs supporting the underside of the composite structure at each side thereof.

9. The improved center plate construction of claim 8 wherein the composite structure includes a central passage therethrough, an annular inner wall between said top and bottom walls defining said passage, said annular wall being cylindrical at its upper section and flared outwardly at its lower section.

10. The improved center plate construction of claim 9 wherein said welding flanges have spaced openings therein and wherein the central section of said annular passage is flared outwardly to a greater degree than the bottom section thereof.

5 11. The improved center plate construction of claim 8 wherein said arcuate longitudinal support member has transverse arms extending therefrom to said welding flanges.

10 12. The improved center plate construction of claim 8 wherein each support means is reinforced approximately centrally thereof by one end of one arcuate longitudinal member at its merger with one of said transverse ribs.

15 13. A railway car body center plate comprising a top wall, a bottom wall for support upon an associated railway car truck bolster, holes extending through said walls for reception of an associated king pin, lateral walls each having pads at its opposite ends to support an associated sliding center sill, spaced transverse ribs connecting the bottom wall to both lateral walls, and a longitudinal support member connected to the bottom of each lateral wall and connected at opposite ends of said support member with respective ribs beneath the related support pads approximately centrally thereof.

20 14. In combination with a railway cushioned underframe wherein a center U-shaped sill member is detached and permitted to drive longitudinally in either direction while sliding on the body center plate, the improvement in center plate construction which comprises a unitary composite structure having a top wall of substantially

25 rectangular shape, a bottom undulated wall defining a central annulus for engagement with a mating truck bolster center plate, side walls sloping outwardly from said top wall to said bottom wall toward a line outside the outer circumference of said annulus, lateral walls extending from said side walls and comprising support means for said sliding sill member, substantially vertical support walls at the outer sides of said lateral walls extending along the length of said lateral walls, attachment flanges

30 disposed outwardly and upwardly along the length of said substantially vertical support walls, a transverse rib supporting the composite structure at each end thereof, and an arcuate longitudinal member extending between said transverse ribs supporting the underside of the bottom wall of

35 the composite structure at each side thereof outwardly of said annulus.
